UNITED STATES PATENT OFFICE.

EDWIN F. M. SPEIDEL AND KARL C. AUGENSTEIN, OF CRANSTON, RHODE ISLAND, SAID AUGENSTEIN ASSIGNOR TO SAID SPEIDEL.

EXTENSION DEVICE.

Application filed August 24, 1928. Serial No. 301,840.

This invention relates to a foldable extension device for a wrist watch strap and has for its object to provide a means for detachably securing the end of one of the sections 5 of the device to the bail of a wrist watch so that the same will not accidentally be disconnected therefrom.

A further object of the invention is the provision of a hook formation on the end of one 10 of the plate sections with a movably mounted closure member for the hook opening so mounted as to positively close the opening to the hook and prevent detachment of a section from the watch.

15 The invention further consists in means for locking the closure member in its working position and the provision of means for assisting in controlling its movement.

With these and other objects in view, the 20 invention consists of certain novel features of construction, as will be more fully described, and particularly pointed out in the appended claims.

In the accompanying drawings:

25 Figure 1 is a top plan view of a watch with an extension device of our improved construction mounted on either side thereof.

Figure 2 is a top plan view of the device with its sections in unfolded position.

30 Figure 3 is a view similar to Figure 2 showing the underside of the sections.

Figure 4 is a bottom view of the end section which detachably engages the watch bail with the closure member in working position.

35 Figure 5 is a perspective view similar to Figure 4 showing the closure member in open position.

Figure 6 is a section on line 6—6 of Figure 4.

40 Figure 7 is a central longitudinal section through the end section, shown in Figure 4, with the closure member in working position.

Figure 8 is a sectional view similar to Figure 7 showing the closure member in open position as illustrated in perspective in Figure 5.

45 In extension devices of the type designed to directly engage the bail of a wrist watch, it is found desirable to provide a means by which the device may be easily and quickly attached or detached to the watch bail and yet one which will positively prevent the device from becoming accidentally detached

from the watch, and in order to accomplish this result, we have formed one end of a plate section of the device into a suitable hook to hingedly engage the bail of a wrist watch and have mounted on this plate section a closure member to slide along the plate and close the entering opening to the hook to prevent detachment thereof from the watch, and in order to positively secure this closure member in its closed or working position, we have formed frictional engaging detent and recess means carried respectively by the closure member and plate section for locking the closure member in working position, and following is a detailed description of the present embodiment of this invention, showing the preferred means by which these advantageous results are accomplished:

With reference to the drawings, 10 designates a wrist watch having bails 11 at either side thereof to which the foldable extension devices designated generally 12 are attached. The extension device consists of a plurality of sections 13, 14 and 15 to the former of which is adjustably secured, in any desired manner, the wrist strap 16, such as by means of a pin 17 mounted in any one of the plurality of positions in the side walls 18 of this end section. These sections are suitably hinged together by means of pivots 19 and 20, extending through suitable ears 21 and 22 on the different sections.

75 The end section 15 which engages the watch has a hook shape formation 23 on one end with a suitable opening 24 for insertion of the watch bail 11 therein, the hook is on the arc of a circle to form a pivotal bearing for swingably or hingedly attaching this end section to the watch bail.

80 In order to close the opening 24 to prevent accidental detachment of this section from the bail 11, a closure member 25 is provided to extend across the opening 24 and has fingers 26 extending therefrom and bent around the edge of the plate 15 to guide and slidably mount the closure member 25 thereon. This member 25 may be moved from the open position illustrated in Figure 5 to the closed or working position illustrated in Figure 4, and securely locked in this position by the detent 27 pressed inwardly from the stock of the closure member to snap into engagement with an opening 28 in the plate section 15. An opening movement of the closure member

25 is limited by stops 29 raised from the stock of the plate 15.

The hook formation is cut as at 30 providing a portion which is folded back upon itself forming a latch 31 to extend through the opening 32 in the intermediate plate section 14 for engagement with the pivotal bar 19 to assist in retaining the device in folded position and prevent accidental opening 10 thereof by a longitudinal strain on the device.

It will be observed that the connection of the plate section to the wrist watch is a simple construction but yet positive in its operation to prevent accidental detachment of the device from the watch but yet allow easy removal by suitable manual manipulation.

The foregoing description is directed solely towards the construction illustrated, but 20 we desire it to be understood that we reserve the privilege of resorting to all the mechanical changes to which the device is susceptible, the invention being defined and limited only by the terms of the appended claims.

25 Claims directed broadly to the features herein shown are presented in our copending application Serial No. 238,405, and also claims to the clasp for the sections herein shown are made the subject of our copending application Serial No. 301,683.

We claim:

1. A foldable extension device for a wrist watch strap comprising a plurality of sections hinged together, hook means carried by 35 the end of one of said sections of a width as wide as the section to detachably engage the bail of a wrist watch and means for locking said section in engaged position.

2. A foldable extension device for a wrist 40 watch strap comprising a plurality of sections hinged together, a hook carried by the end of one of said sections and of a width as wide as the section to detachably engage the bail of a wrist watch and a closure member mov- 45 ably mounted on said section to close the en-

tering opening to said hook to hold the section in engagement with the watch.

3. A foldable extension device for a wrist watch strap comprising a plurality of plate sections hinged together, a hook carried by the end of one of said sections to detachably engage the bail of a wrist watch and a closure plate movably mounted on said section and snugly fitting the section throughout the length of the closure plate and the width 55 of the section plate to close the entering opening to said hook to hold the section in engagement with the watch, and means for limiting the movement of said plate.

4. A foldable extension device for a wrist watch strap comprising a plurality of plate sections hinged together to fold one over the other, the end of one of said sections having a hook formation with an opening to receive and swing on the bail of a wrist watch, a closure member on one side of said section having fingers bent around said plate to guide said member and permit sliding movement thereof on the plate to close the opening to the hook formations, projections raised from said plate to limit the opening movement of the member, and detent and recess means respectively on said member and plate to hold the member in closed position.

5. A foldable extension device for a wrist watch strap comprising a plurality of plate sections hinged together to fold one over the other, the end of one of said sections having a hook formation with an opening to receive and swing on the bail of a wrist watch, a closure member on one side of said hook section having fingers bent around said plate section to guide said member and permit sliding movement thereof on the plate to close the opening to the hook formation.

In testimony whereof we affix our signatures.

EDWIN F. M. SPEIDEL.
KARL C. AUGENSTEIN.
